UNITED STATES PATENT OFFICE

2,284,440

EAVE TROUGH PROTECTOR

Joseph V. Morrissey, Waukegan, Ill., assignor to
The American Steel and Wire Company of New
Jersey, a corporation of New Jersey

Application August 4, 1940, Serial No. 351,301

5 Claims. (Cl. 108—30)

This invention relates to improvements in eave trough protectors.

It is an object of this invention to provide an eave trough protector which may be readily applied to standard forms of eave trough.

My invention contemplates a light weight screen-type of protector formed in and capable of being applied in one continuous piece throughout the length of the eaves trough, thereby eliminating overlaps, seams and splicing heretofore employed with screen-type protectors.

I further have in view to provide a protector of the character stated having integral edge reinforcements, thereby eliminating binding or added strengthening as has been heretofore employed, and providing for ease of attachment of the protector.

Another object is to provide and maintain flexibility of the protector, whereby the same may be rolled for shipping and more easily applied to the eave trough.

Additional objects and advantages will become apparent from the following description taken in connection with the accompanying drawing, wherein:

Fig. 1 is a perspective view, partly in section, showing an embodiment of my invention;

Fig. 2 is a cross-sectional view thereof;

Fig. 3 is a view similar to Fig. 2 showing another manner of applying the protector to another form of eave trough; and

Figs. 4, 5 and 6 are fragmentary plan views of different forms of the protector.

Referring to the drawing, 2 designates a portion of the side or frame of a house or building having a sloping roof 3 composed of shingles or the like, said roof overhanging the wall 2 and forming an eave therewith.

Referring to Figs. 1 and 2, an eave trough 4 of conventional form is positioned immediately below the eave, said trough including an inner wall 5 disposed against the building wall or frame 2, a bottom 6 and an outer sloping wall 7 terminating in an inwardly projecting flange 9, said flange extending longitudinally of the trough.

Hangers or supports 11 of any suitable type may be employed for securing the trough 4 in position. For example, said hangers 11 include spacing sleeves 12 extending transversely throughout the uppermost portion of the eave trough and receiving nails or spikes 13 extending from the outer edge portion of the trough through said sleeve, through the wall 5 of the

trough and into the side or frame 2 of the building.

For covering and protecting the upper open portion of the eave trough 4, I provide a protector 14 comprising a continuous one-piece screen or wire mesh extending longitudinally along the trough. Said protector is of uniform mesh and thickness, having integrally reenforced or selvage longitudinal edges 16 whose thickness does not exceed the thickness of the screen.

Figs. 4, 5 and 6 illustrate several forms of my protector 14, each including a plurality of integrally woven flat wires or strips 17. For example, Fig. 4 shows a series of the flat wires 17 at the edges of the protector; Fig. 5, flat strips 17 alternating with the wires of the mesh or screen; and Fig. 6, a flat wire at the immediate edge, and a plurality of flat wires inwardly of an intervening wire of the mesh or screen. Other similar designs and arrangements of the flat wires may likewise be employed for forming the selvage edges 16, the thickness of the flat wires 17 being preferably substantially that of the wire of the mesh so as to provide a thin structure reinforced for strength.

In applying the protector 14, one longitudinal selvage edge 16 is slid or entered beneath the shingles of the roof 3 between said shingles and the wall or structure 2, whereupon the protector may be inclined downwardly into supporting engagement by its other edge 16 with the supports or hangers 11. Due to the fact that the selvage edge 16 is of minimum thickness, the same may be easily entered beneath the shingles of the roof 3 without materially affecting said shingles or loosening the same.

When the protector 14 is applied as stated, the lower outer edge 16 thereof is disposed below the trough flange 9, whereby the protector is confined against accidental disengagement, in the event that it becomes loosened at its point of engagement with the shingle.

As desired, the slope of the protector 14 substantially coincides with that of the roof 3, whereby the appearance of the assembly is enhanced. However, where necessary, the flexibility of the protector permits transverse bending or bowing of the same to accommodate a protector to narrower widths of eave trough.

Considerable advantage is attained by the use of my invention due to the fact that the protector 14 may be made in one continuous piece, whereby the same may be rolled for shipping and for ease of application to an eave trough. Such a construction is highly economical and

practical as compared with former types of screen or mesh protectors.

Fig. 3 illustrates the application of the protector 14 to a different style of eave trough having hangers 11^a disposed over the top of the trough. In such case, the lower outer edge 16 of the protector rests upon said hangers and is preferably secured thereto by ties or clips 18.

It will be seen that the protector of my invention will adequately cover and protect the eave trough when positioned therein, preventing the entrance of leaves or other foreign matter to the trough and permitting rain water flowing downwardly from the roof to enter the trough.

Various changes and modifications are contemplated within the scope of the following claims.

I claim:

1. The combination with an eave trough of trough supports therefor, and a protector of flexible wire screen having at least two substantially flat longitudinal wires forming a reinforced selvage edge of appreciable width and not exceeding the thickness of the screen, said protector extending continuously in one piece longitudinally of the trough, and having its selvage edge entered beneath and held by the shingles of the roof, the other longitudinal edge of the protector being supported adjacent the outer free edge of the trough in the plane of inclination 30 of the protector downwardly from the roof.

2. The combination with an eave trough, of trough supports therefor, and a protector extending continuously in one piece longitudinally of the trough, said protector comprising a flexible wire screen having its longitudinal edges each provided with at least two substantially flat longitudinal wires forming reinforced selvage edges of appreciable width and not exceeding the thickness of the screen, the inner edge of said protector being entered beneath and held by the shingles of the roof, and the outer longitudinal edge thereof being supported adjacent the outer free edge of the trough in the plane of inclination 35 of the protector downwardly from the roof.

3. The combination with an eave trough, of

trough supports therefor, and a protector extending continuously in one piece longitudinally of the trough, said protector comprising a flexible wire screen having its longitudinal edges each provided with at least two substantially flat longitudinal wires forming reinforced selvage edges of appreciable width and not exceeding the thickness of the screen, the inner edge of said protector being entered beneath and held by the shingles of the roof, the outer longitudinal edge thereof engaging the trough supports in the plane of inclination of the protector downwardly from the roof, and fasteners securing said outer protector edge to the supports.

4. An eave trough protector comprising a continuous strip of flexible wire screen having at least two substantially flat longitudinal wires forming a reinforced selvage edge not exceeding the thickness of the screen for ease of insertion thereof beneath the shingles of a roof, said selvage edge portion being of a width to provide a substantial anchorage for the protector upon the said insertion thereof, the over-all width of the protector being sufficient to span the open face of an eave trough by transverse inclination of the protector downwardly from the said inserted edge thereof for supporting engagement of its other longitudinal edge adjacent the free longitudinal edge of the eave trough.

5. An eave trough protector comprising a continuous strip of flexible wire screen having opposite flat reinforced selvage edges each including at least two longitudinal flat wires, said edges not exceeding the thickness of the screen whereby either of said edges may be easily inserted beneath the shingles of a roof, said selvage edges being of a width to provide a substantial anchorage for the protector upon said insertion of one of said edges, the over-all width of the protector being sufficient to span the open face of an eave trough by transverse downward inclination of the protector from the said inserted edge thereof for supporting engagement of its other longitudinal edge adjacent the free longitudinal edge of the eave trough.

JOSEPH V. MORRISSEY.
